UNITED STATES PATENT OFFICE.

AUGUST G. BERTRAM, OF NEW YORK, N. Y.

VALVE-ACTUATING MECHANISM.

Application filed August 14, 1922. Serial No. 581,716.

To all whom it may concern:

Be it known that I, AUGUST G. BERTRAM, a citizen of the United States, and a resident of the city of New York, borough of 5 Manhattan, in the county and State of New York, have invented a new and Improved Valve-Actuating Mechanism, of which the following is a full, clear, and exact description.

10 This invention relates to a valve actuating mechanism, and has for an object the provision of means whereby fluid valves, such as those used in modern plumbing, may be very easily operated without the use of 15 cumbersome, large projecting heads and valves extending from the surface of the walls and accessories within the room, such as a bath-room.

Another object resides in the provision of 20 means whereby the valve can be very easily operated by simply pushing a button disposed in the wall.

A further object resides in the provision of means whereby the valve is opened by 25 merely pushing the button and is also closed in as easy a manner.

A still further object resides in the particular construction and arrangement of parts which are hereinafter described and 30 claimed and shown in the accompanying drawings.

The invention is illustrated in the drawings, of which—

Figure 1 is a section through a bathtub 35 showing the disposition of the buttons above the head of the tub in the wall.

Fig. 2 is a partial vertical section taken through the device and the valve, showing the valve closed.

40 Fig. 3 is a similar view showing the valve open.

Fig. 4 is a section taken on the line 4—4 of Fig. 3.

Fig. 5 is a section taken on the line 5—5 45 of Fig. 3.

The form of the invention shown in the drawings is a preferred form, although it is understood that modifications in the construction and arrangement of the parts and 50 in the character of the materials used may be adopted without departing from the spirit of the invention.

The invention as illustrated in the drawings contemplates the control of water 55 through pipes 1 and 2 connected by a T head or elbow 3 in which a valve stem 4 is slid-

able, carrying on one end a valve 5, the other end 6 of the stem connected to a head portion 7 adapted to be depressed by the hand or finger in a manner hereinafter to be described. Intermediate the handle of the stem of the valve, a portion of considerably reduced diameter is provided which forms at its ends with the main portion of the stem shoulders 9 and 10. Along this portion of 60 reduced diameter a sleeve 11 is adapted to move, said sleeve at one end having a flange 12 extending outward at right angles thereto. Surrounding the stem 6 along a certain portion is a sleeve 13 fastened at one end 65 to the bottom of a casing 14 which may be attached to any suitable support, such as the rear of the wall on which the depressible member or button 7 is disposed. A spring 15 surrounds the stem 6 within the sleeve 13 70 and bears against the shoulder thereof, tending to force the stem in a direction to close the valve 5.

Adjacent one end of the sleeve 13, I fasten a pair of spring fingers 16 which at 80 their outer ends have dependent portions 17 adapted to embrace the stem 6 near one end thereof. The stem portion along this part is provided with a plurality of notches 18 disposed on opposite sides thereof and 85 adapted to receive the ends of the fingers 16. These notches are so formed as to prevent the movement of the stem 6 in one direction, namely, that in which the valve 5 would tend to close, while the ends of the 90 fingers 16 are engaged in the notches. These fingers 16 are held forward against the stem 6 by any suitable means, such as leaf springs 18^a disposed within the casing 14 and having one end bearing against the fingers 16. 95 The outer end of the stem 6 is provided with a cuplike sleeve 19 extending into an aperture in the wall 20 and adapted to be depressed by the finger. The casing 14 is carried on the plate 21 fastened to the wall 100 20 by any suitable means, such as screws 22. The plate 21 is also provided with a cylindrical flange portion 21^a within which the ends 7 of the stem 6 slide and which is embraced by the sleeve 19 forming a sort of 105 bearing therefor.

In the operation of the device, assuming the parts in the position shown in Fig. 2, if a person desires to start the flow of water, the finger is pressed against the sleeve 19, 110 which moves the stem 6 to the left. A sufficient movement will cause the engage-

ment of the fingers 16 with the first set of notches 18. These fingers will be held in the notches by springs 18^a. A retraction of the stem 6, due to the force of the spring 15, is provided by this engagement. The valve 5 is now unseated to a slight degree. A further depression of the stem will cause the engagement of the fingers 16 with another set of notches further along the stem to cause the valve to be further opened.

At a certain point in the travel of the stem, the shoulder 10 engages the sleeve 11 and forces it to the left. The sleeve 11 will move to the left until the flange 12 thereon rubs with any desired force against the inner face of the finger 16. These fingers 16 are disposed at an angle to the stem 6 so that as the sleeve 11 is moved further to the left, the flange 12 thereon tends to spread the fingers 16 against the action of the springs 18^a thereby causing the disengagement of the ends 17 of the fingers 16 from the notches 18. As soon as this disengagement takes place, the spring 15 forces the stem entirely to the right, whereby the valve 5 is closed. As the stem moves to the right, the shoulder 9 will engage with the sleeve 11 and move it to the right, releasing it from contact with the fingers 16. This release is necessary because the pressure of the springs 18^a on the fingers 16 will cause the sleeve 11 to be maintained in a fixed position, due to the action of the springs 18^a. Until this sleeve is released, the ends 17 of the fingers 16 are not in a condition to reengage the notches if the stem 6 should be again depressed.

It will, therefore, be observable that in order to cause the water to flow it is merely necessary to depress the button or sleeve 19 a desired amount, the stem 6 being automatically held in the desired position. To release the device and shut off the water, it is merely necessary to further depress the button portion and then quickly release it, whereupon the button will return to normal position and the valve 5 will be closed.

What I claim is:—

1. A valve actuating mechanism which includes a stem having a plurality of notches therein, latching fingers adapted to engage in the notches and restrain the movement of the stem in one direction, and means carried

by the stem to disengage the fingers from the notches after the stem has been moved a predetermined distance.

2. A valve actuating mechanism which includes a stem having a plurality of notches therein, latching fingers adapted to engage in the notches and restrain the movement of the stem in one direction, means carried by the stem to disengage the fingers from the notches after the stem has been moved a predetermined distance, and means engaging the stem and restraining it to normal position when the stem has been turned into the notches.

3. A valve actuating mechanism which includes a valve stem having a plurality of notches therein, latching fingers adapted to engage in said notches, springs bearing against the fingers to press them forward into said notches as the stem is moved, a sleeve slidable on said stem, a flange on the notches, whereby the fingers are moved by the flange when the stem has been depressed beyond a certain point to the right, the sleeve 11 and move it to the right, releasing it from contact with the fingers 16. This release is necessary because the pressure of the springs 18^a on the fingers 16 will cause the sleeve 11 to be maintained in a fixed position, due to the action of the springs 18^a. Until this sleeve is released, the ends 17 of the fingers 16 are not in a condition to reengage the notches if the stem 6 should be again depressed.

It will, therefore, be observable that in order to cause the water to flow it is merely necessary to depress the button or sleeve 19 a desired amount, the stem 6 being automatically held in the desired position. To release the device and shut off the water, it is merely necessary to further depress the button portion and then quickly release it, whereupon the button will return to normal position and the valve 5 will be closed.

AUGUST G. BERTRAM.
